UNITED STATES PATENT OFFICE

ANDREW FRASER, OF SAN FRANCISCO, CALIFORNIA.

ORE-CONCENTRATING MACHINE.

SPECIFICATION forming part of Letters Patent No. 487,261, dated December 6, 1892.

Application filed December 30, 1891. Serial No. 416,588. (No model.)

To all whom it may concern:

Be it known that I, ANDREW FRASER, a citizen of the United States, residing in the city and county of San Francisco, State of California, have invented certain new and useful Improvements in Ore-Concentrating Machines; and I hereby declare the following specification and the drawings accompanying and forming a part of the same to be a full and exact description of my improvements.

My invention relates to that class of machines known as "concentrators" or "vanners" for selecting or concentrating minerals from crushed ore, sand, or other earthy matter by means of agitation while the material is suspended in or saturated with water; and it consists in the construction, arrangement, and combination of parts, substantially as will be hereinafter described and claimed.

Referring to the drawings, Figure 1 is a plan view of a machine constructed according to my invention, with some of the details removed. Fig. 2 is a side elevation of the same machine. Fig. 3 is an end view of Figs. 1 and 2. Figs. 4, 5, and 6 are details showing the manner of constructing the pivotal supports for the apron and its connected parts.

Similar letters of reference are employed on the different figures to indicate corresponding parts of the machine.

In notation, A A A represent the timber framing or foundation on which the machine rests.

B is the apron or continuous web on which concentration is performed.

C' is the main or driving drum, around which the apron passes.

C² is the idle-drum, over which the apron passes at the rear of the machine.

C³ are intermediate supporting-rollers that sustain the apron and turn up the edges to form flanges.

C⁴ are deflecting-rollers beneath the apron to lift it clear of the machinery.

D' D² are pivoted supports, on which the apron and its supporting-frame are mounted.

E' is the crank-shaft for producing an oscillating movement of the apron and its connected parts.

E² E³ are the cranks at each end of the main driving-shaft.

E⁴ is the intermediate shaft set at the axis of the apron's oscillating movement.

F' F² are links or connecting-rods for operating the apron and its supporting-frame. 55

G is a gear-wheel driving the main drum C'.

H' is a worm or tangent wheel imparting motion to the wheel G.

H² is the shaft and axis of the worm-wheel H'.

H³ H⁴ are driving-bands operating the feed motion of the apron. 60

I is the main driving-pulley for applying power to the machine.

J is a tank, into which the concentrates are discharged from the apron B. 65

K is a distributing-box, from which material is fed to the apron B.

L are water-pipes for supplying the apron B.

L² are cocks for regulating the amount of water supplied to the apron. 70

M are the bearings of the crank-shaft E'.

N is a coupling connecting the two parts of the shaft E'.

O' O² are conical drums regulating the rate of lineal movement of the apron B. 75

P is a pedestal for receiving the pivotal supports D' D².

Q Q are channel-bars forming the sides of the main frame of the apron B and its details.

R is one of the brackets on which the rear drum C² is mounted. 80

S is one of the adjusting-screws for moving the drum C².

T is the rear end of the apron, where the waste material is discharged. 85

U is a hand-wheel for shifting the band H⁴ and regulating the speed of the apron B.

V is a stop-cock controlling the supply of water to the apron B.

W is a hose-pipe for conveying water to the tank J. 90

X is the bearing of the pivotal shaft E⁴.

Y Y are detents to keep the bracket or support D central on the foot-step P.

Z is the nipple for connecting hose-pipe. 95

w is the hose-pipe to collecting-tank J.

a is the screw-joint in the connecting-links.

e is the conical extension on rollers C³.

m is the convex face of the pivotal supports D. 100

n is the flange to cover convex bearings of D.

o represents screws to adjust drums C⁴.

s represents brackets to support drums C⁴.

In that class of concentrating-machines to which my invention belongs the continuous aprons, in addition to their lineal or feed movement, require agitation by lateral, circular, or oscillating motion, or combinations of these; but of whatever kind, this agitating movement has hitherto been produced so as to react upon the framing of the machine, and, 10 usually, at or near the top, causing destructive vibration and consequent wear of the parts. To obviate this objection, I dispense altogether with the usual main frame and mount the apron B and its connected parts upon two or 15 more supporting-brackets D' D², which are pivoted and rest upon the pedestals P, set upon the foundation.

To avoid the effects of the agitating movement, which is in this case a rocking or oscillating one, I place the crank-shaft E in bearings M M, also set upon the foundation, and arrange the connecting-links F' F² in a nearly-vertical position, thus changing the line of force and reaction of the apron B and its parts 25 from a horizontal to a vertical plane and to the foundation A. The movement of the apron and its frame Q, being portions of a revolution around the axis at E⁴, and the connecting-rods F' and F being tangential thereto, 30 there is no vibrations or strains in a horizontal direction to cause wear or derangement.

The crank-shaft E' has a main driving-pulley I and a truncated cone-pulley O', also cranks E³ and E³ at its ends. For convenience 35 in erecting and to provide for placing and removing the pulleys I and O', I make the shaft E' in two pieces and join them by a coupling N.

To adjust the apron B and frame Q and keep the working surface level when in a neutral or central position, I provide joints a a in 40 the connecting-links F' and F², so the apron B can be readily adjusted and kept in a proper position by shortening or extending these links and without other adjustment of any 45 kind. The apron B is made of any flexible material, either fibrous or of gum, and is strained so as to lie flat by means of the pulley or drum C², which can be adjusted forward or back by means of the movable brackets R and the screws S, as shown in Fig. 2.

To perform the feed or lineal movement of the apron B, motion is taken from the conical drum O' by the band H⁴ to the second conical drum O² on the shaft E⁴, and then by another band H³ from the shaft E⁴ to the shaft H², as shown in Fig. 3. This shaft H² is provided with a worm or tangent screw H', gearing into the wheel G, which drives the drum C' and the apron B at a slow rate, which can 55 be varied by shifting the band H⁴ on the conical drums O' and O². This adjustment is made by means of a common shifting-fork, operated by a screw and the hand-wheel U. (Shown in Fig. 3.)

60 The ore or material to be concentrated is fed from the distributing-box W and falls on the apron B in a thin stratum across its width

and is taken up and moved toward the rear end of the machine by the action of the water escaping at the cocks L², falling on the apron 70 and flowing toward the lowest end at T. The concentrates or particles of mineral matter being heavier than the sand or earthy matter settle at the bottom, adhere to the apron, and are carried back and around the drum C' to 75 fall or be washed off at the tank J.

The material on the apron B is prevented from spilling over the sides by a flange or lip turned up by the conical extensions e e of the bearing-rolls C³, as shown in Fig. 1. This 80 raised lip or flange becomes flat again as the apron B approaches the drum C'. The gangue or waste material falls off the apron B as it passes over the rear drum C².

The deflection of the apron B by the drums 85 or rollers C⁴ is to raise the bottom part clear of the machinery and parts beneath and prevents vibration of the web, which might otherwise take place. The drums C² are mounted on pivoted brackets S, adjusted by the screws 90 o, so that the lower reach of the apron may be set up or down accordingly.

Water is introduced through pipes L, and in the horizontal section above the table I insert a number of adjustable cocks L², which 95 can be set to distribute the water uniformly over the surface of the apron B, or an increased amount can be supplied at the sides or in the center, the supply as a whole being controlled by a valve V in the usual manner. 100

The hose-pipe W is connected from the water-supply to the bottom of the tank J to provide water required there.

Referring to Figs. 4, 5, and 6 these represent one of the pivotal brackets or supports 105 on which the apron B and its frame are mounted and the manner of constructing the foot-step at the bottom.

In the partial end view, Fig. 4, the pieces Y Y Y are detents to retain the bracket or 110 support D in a central position over the pedestal P. The top of the pedestal P is flat and the bearing of the bracket resting thereon is curved and also indented, as shown at m in the section, Fig. 5, so as to form protecting 115 lips or flanges n all around the bearing and protect it from grit and sand.

The bearing X for the shaft E⁴ is formed integrally with the bracket or support D, as 120 shown in the section, Fig. 6. This bracket D, as may be seen, is made to span the main frame of the apron B and to receive at each side the channel-bars Q, which are the main members of this frame.

Having thus described the nature and objects of my invention, also the manner of constructing and applying the same, what I claim as new, and desire to secure by Letters Patent, is—

1. In an ore-concentrating machine as herein described, an oscillating frame having a rocking motion on rolling faces, as herein described, placed at or near the plane in which the actuating-cranks are situated and at the

base of the machine, so that the action of the cranks will be transverse to the rolling supporting-faces and in a vertical or nearly-vertical plane and so the momentum of the 5 vibrating table and its attachments will fall vertically on the foundation-frame, in the manner substantially as and for the purposes specified and set forth.

2. In an ore-concentrating machine, an endless apron and supporting-frame for the same having a rocking or oscillating movement, as herein described, mounted on pivotal rolling supports on the foundation-frame, and a crank-shaft to actuate the apron, also set on 10 the foundation-frame and connected to the apron-frame by links, which can be lengthened or shortened, so that the upper or working surface of the apron can be set by such 15 adjustment and the ore be equally distributed 20 thereon, in the manner substantially as and for the purposes specified.

3. In an ore-concentrating machine having an oscillating movement, as herein described, rolling supports for the same placed at or on 25 the foundation-frame, branched supporting-standards resting on the rolling-faces and extending to the outer rails of the apron-supporting frame, so as to dispense with framing other than the foundation, in the manner and for 30 the purposes herein set forth and described.

4. In an ore-concentrating machine, an os-

cillating apron-supporting frame supported on branched standards provided with rolling bearings set on the foundation-frame, an actuating crank-shaft set at the side of the machine also on the foundation-frame, the shaft divided into two coupled parts, and a driving-pulley placed between its bearings, and the cranks overhung at each end, so that they can be made solid with the shafts and the connections conveniently removed without disturbing the driving-gearing, substantially in 35 the manner and for the purpose specified.

5. In an ore-concentrating machine, an oscillating apron-supporting frame with an endless apron thereon, the frame mounted on standardssupported on rolling bearings placed on the foundation-frame, and an intermediate feeding-shaft mounted in the supporting-standards near the center of their oscillation and connected to the main or crank shaft by means of a belt and conical drums also to the driving-apron drum by tangent gearing, in the manner substantially as and for the 40 45 50 purposes set forth.

In testimony whereof I have hereunto affixed my signature in the presence of two witnesses.

ANDREW FRASER.
